CLAIM

The ornamental design for a tri-fold pocket as shown and described.

DESCRIPTION

FIG. 1 is a perspective view of a tri-fold pocket in an unfolded, flat, closed configuration according to my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left-side elevational view thereof;

FIG. 7 is a right-side elevational view thereof;

FIG. 8 is a top plan view thereof with the mouth of the pocket in an open configuration;

FIG. 9 is a perspective view thereof;

FIG. 10 is another perspective view thereof;

FIG. 11 is a perspective view thereof in a folded configuration;

FIG. 12 is a front elevational view thereof;

FIG. 13 is a rear elevational view thereof;

FIG. 14 is a top plan view thereof;

FIG. 15 is a bottom plan view thereof;

FIG. 16 is a right-side elevational view thereof;

FIG. 17 is a left-side elevational view thereof; and,

FIG. 18 is a perspective view thereof.

The evenly dashed broken lines along the perimeter of the tri-fold pocket depict stitching that forms part of the claimed design. The evenly spaced horizontal and vertical broken lines within illustrated rectangles on the surfaces of the tri-folded pocket depict press fasteners which form no part of the claimed design. The evenly spaced broken lines in FIG. 18 depicting a cap form no part of the claimed design.
